(57) **CLAIM**

The ornamental design for a device for supporting an art object in spaced relation to a wall surface, as shown and described.

DESCRIPTION

FIG. 1 is a perspective view of our device for supporting an art object in spaced relation to a wall surface;

FIG. 2 is a left side view thereof; the opposite side being a mirror image thereof;

FIG. 3 is a rear view;

FIG. 4 is front view; and,

FIG. 5 is a top view; the bottom view being a mirror image thereof.
